ATTORNEY

BUTTER CONTAINER OR THE LIKE

The present invention is directed to a container for storing and serving of butter or the like. The container is simple to open and close, easy to clean, provides an effective moisture and odor barrier for the contents of the container, and enables a rapid and continuous cooling of the contents of the container to be effected. More particularly, the invention is directed to a container which, by its construction, retains the contents a substantial distance from its sealing surfaces and additionally provides an area upon which serving implements may be cleaned also without contacting those sealing surfaces.

A construction incorporating these features, therefore, provides improvements and advantages over the prior art containers, particularly with respect to continued effective sealing even during extended periods of use. Such is accomplished primarily due to the recessed portion of the supporting container as well as the ledge that surrounds that portion.

These as well as other advantages will become more apparent when reference is made to the ensuing description of a preferred embodiment of the invention in which:

FIG. 1 is an exploded perspective view of a butter container or the like including the supporting container and its associated cover;

FIG. 2 is a side elevation view of these same two components; and,

FIG. 3 is a sectional end elevation view taken along line 3-3 in FIG. 2.

Briefly, the present invention includes a base and a cover. The base has a substantially flat recessed, pebbled, inner surface, an upwardly extending integral side wall that terminates in an outwardly extending ledge and a downwardly extending ledge and an outwardly and upwardly curved flange also integral with the side wall. The cover for the base is a hollow box-shaped member having a top wall and a continuous integral side wall affixed to and extending downwardly from the periphery of the top wall. The underside of the cover is open, and a continuous outwardly extending peripheral flange is positioned adjacent the lower edge of the cover side wall. The cover fits over the base with a lock engagement since the area of contact between the base and the cover a locking taper is provided.

Referring specifically to the drawings, the base 8 includes a substantially flat recessed surface 10 having a textured or pebbled effect that is produced by hemispherical extensions protruding slightly above the flat surface and in random orientation as best shown in FIGS. 1 and 3. The surface 10 has an integral upwardly projecting peripheral side wall 12, the upper edge of which is affixed to an outwardly extending peripheral ledge 14. This ledge in turn is integral with and supports a downwardly directed sealing wall surface 16 that terminates in an upwardly curved handle-like flange 18. This particular base construction provides a rigid configuration and also maintains any contained foodstuff in a position out of close proximity to sealing wall surface 16.

As can be readily seen upon continued reference to the drawings, isolation of the container foodstuff from the sealing wall surface is generally effected by the ledge 10. A portion of this ledge is also textured in a

fashion similar to the recessed surface 10 and side wall 12. And as is evident from FIGS. 1 and 3, the textured portion terminates in a relief 30 immediately adjacent sealing wall surface 16. The ledge and side wall thereby further provide a convenient structural arrangement upon which a user may readily clean any implement employed in dispensing the foodstuff without inadvertently or otherwise contacting the sealing wall surface.

The handle-like flange 18 is peripherally positioned around the base and is preferably integral with the sealing wall surface 16. The flange 18 curves upwardly and outwardly to permit insertion of the fingers enabling a user to easily grasp the container both in its covered and uncovered condition. Additionally, such flange tends to rigidify the base structure and maintains the sealing wall surface in a generally stable position so that an effective seal may be retained between the base and cover.

The cover 21 is a hollow, box-shaped member having a top wall 22, end walls 24 and side walls 26. Junctures between these walls are preferably rounded to permit easy cleaning. A continuous, outwardly extending flange 28 at a position intermediate the top wall and the terminal edge 30 of the end and side walls. Flange 28, however, is more closely positioned to the terminal edge and lends support thereto. The flange extension is somewhat less than that of the handle-like flange 18 and therefore the user can place his fingers between the two when removing the cover while at the same time grasping flange 28.

The cover is preferably fabricated from low density polyethylene, thus providing the cover with a flexible resiliency that enables it to be slipped over the base 8. In this relationship, the lower inside surfaces of walls 24 and 26 sealably engage against the continuous peripheral sealing wall surface 16 of the base. Likewise, due to the cantilevered effect of the downwardly extending sealing wall surface 16, additional flexibility is achieved for this portion of the base despite the presence of flange 18. It should be particularly noted that the contact area 32 between walls 24 and 26 and wall 16 is large, and that each is tapered at approximately 2°. This is a locking taper that insures a tight seal between the base and the top. Preferably, the base is made from polypropylene but other materials may be employed with equally good effects.

The pressure contact points for the cover on the base are at the four corners of the base. The walls 24 and 26 are tightly stretched between the four corners to maintain the inside surfaces of walls 24 and 26 in taut engagement with base wall 16 between the corners thereby providing an effective seal along the entire peripheral wall 12.

The textured or pebbled surface shown in FIGS. 1 and 3 effectively resists marring resulting from using the base as a cutting board for the contents of the container. This surface also aids in minimizing sliding of the contents on the base. When items such as butter or cheese are placed on the base, small vacuums are formed between a flat surface on the item and many of the recessed areas between the "pebbles". This "vacuum effect" also aids in minimizing movement of the item on the base.

The container is particularly directed to the storage of perishables such as elongated pieces of butter,

cheese, meat loaf or the like, but it obviously can be used for other consumables.

The invention may be embodied in other specific forms without departing from the spirit of the essential characteristics thereof. The present embodiment therefore is to be considered in all respect as illustrative and not restrictive, the scope of the invention being dictated by the appended claims rather than by the foregoing description, and all changes which come within the meaning and range of equivalency of the claims are therefore intended to be embraced therein.

I claim:

1. A storage container adapted to hold consumable food-stuff and the like and comprising:

a base having a recessed inner surface integral with an upwardly extending side wall, said side wall being further characterized by an outwardly extending ledge and downwardly projecting sealing wall that terminates in an upwardly curved flange integral with said sealing wall;

a cover having a top wall and side walls, said side walls including a contact area that is adapted to

sealably engage the exterior surface of said sealing wall and which area is further supported by an outwardly extending peripheral flange positioned proximate the uppermost portion of said contact area.

2. A vapor-tight plastic container of a rectangular cross-sectional configuration for storing perishables and the like comprising:

a base including a circumferential ledge from which extend downwardly directed side walls and a sealing wall substantially separated from said side walls, said side walls being integrally attached to an inner surface that is recessed with respect to said ledge and said sealing wall terminating in an upwardly curved handle-like flange; and,

a box-shaped cover having integral top and side walls, said side walls including an inner contact area that sealably engages said sealing wall of the base and further including an outwardly extending peripheral flange positioned proximate the uppermost portion of said contact area.
